2 Claims

ABSTRACT OF THE DISCLOSURE

A binding for looseleafs having a base, a flexible back connected to one edge of said base and a separate cover having a folded edge adjacent the flexible back. The back has a series of pairs of perforations and the free end of the back lies over the looseleafs. The folded edge also has a pair of perforations located from its end a distance that covers two successive pairs of perforations of the back. A string having two free portions is fixed to the base.

The present invention relates to looseleaf binders of adjustable thickness especially adapted to join together documents such as printed accounting sheets in increasing number and capable of reaching a considerable height, in the order of 15 centimeters.

The binder according to the invention offers the advantage that it allows reading, in a completely flat condition, of any of the documents that it contains even if this document is accordion pleated. Besides, it allows for its contents to be indicated on an extensible label that unrolls over its back as the documents accumulate.

This binder is made up of a rigid base connected to a 35 flexible back formed with a series of perforations, of a flexible string welded to the base and, after extending through the documents to be bound, going through one or the other of the pairs of perforations of the back to thereafter be locked by an independent cover also comprising a pair of perforations formed in a fold, the length of which is greater than the space separating two successive pairs of perforations of the preceding flexible back.

A better understanding of the invention will be afforded by the description that follows having reference to the appended drawings wherein:

FIGURE 1 is an exploded perspective view of the binder of adjustable thickness according to the invention; and

FIGURE 2 is a longitudinal cross-sectional view of the said binder.

The drawings show that the binder according to the invention is made up of a main element A and of a cover B.

Element A itself is formed of a rigid cardboard base 1 and of a flexible back 2. This flexible back 2 is formed with two rows of paired perforations 3 along its full length, the latter corresponding to the total maximum height of the stack of documents that can be bound by this binding.

Immediately beneath the base plate 1 is welded a plastic string 4 that comes out at 5 and 5' inwardly of the back 2 and which is adapted to go through the documents D before coming out through the paired perforations 3.

The cover element B is a rigid plate 6 having a folded flap 7 provided with a pair of perforations 8. As shown in FIGURE 2, the strings 5, 5' after extending through the documents D go through a first pair of perforations 3 of the back 2 then through the perforations 8 of the folded flaps 7 and finally return inwardly toward the back 2 through a second pair of perforations 3. The fact that the flap 7 covers two successive pairs of per-

2

forations 3 results in that the strings 5, 5' in returning inwardly toward the back 2 are clamped between the said flap 7 and the horizontal part of the back 2, thus fixing the ends of the strings to the length corresponding precisely to the thickness of the stack of documents inset in the binding.

It will be noted that the cover 6 extends flush with the back 2 whereas base 1 only extends rearwardly to the level of the used perforations 3.

It will be understood that, between the rows of perforations 3, a label 9 (FIGURE 4) may be disposed to extend over the full length of back 2 and only the portion of which, located between the weld 4 and the back edge of cover 6, is visible so that a greater portion of the back 15 2 becomes visible as the documents pile up at the same time revealing successive zones of the label. It is then possible to mark on the label the location of the documents as they are inserted.

I claim:

20 1. In a looseleaf binder of adjustable thickness for the binding of looseleafs having holes along one edge thereof; said binder having a base, a flexible back fixed at one end to one edge of the base and having a free edge; the back formed with two parallel rows of aligned paired holes, each row extending between the base edge and the free edge of the flexible back, the flexible back having a length such that a portion thereof may be folded over the top of the looseleafs at the perforated edge thereof when the looseleafs are inserted in the binder, the binder 25 also having a cover intended to be disposed over the looseleafs, the improvement in the combination therewith comprising:

(a) a flap hingedly connected along one edge thereof to one edge of said cover whereby to be foldable beneath said cover to lie over the portion of said flexible back that is to lie over the looseleafs;

(b) said flap formed with two holes spaced to correspond each with one row of holes of said flexible back and located away from the free edge of said flap a distance greater than that separating two consecutive holes of said flexible back;

(c) two strings secured at one end to said base adjacent said flexible back and located to correspond to the holes through the looseleafs whereby, in use, said strings extend successively through the aligned holes of the looseleafs through two holes of the flexible back cover standing over the looseleaf holes and through the holes of said flap; the strings then project away toward the free edge of said flap, bend down and in reverse beneath said flap and are then inserted through holes of said rows immediately ahead of the first flexible back holes through which the strings first extend so that the cover, flexible back and looseleafs are tightly bound together.

55 2. A combination as claimed in claim 1, including a label on the flexible back, between said rows of back holes to mark the location of looseleafs as they are inserted in said binder.
